ADJUSTABLE CAR RETARDER

Ray W. Mars, Chicago, and Robert W. Rantz, Evergreen Park, Ill., assignors to American Brake Shoe Company, New York, N.Y., a corporation of Delaware
Filed Apr. 23, 1964, Ser. No. 362,045
8 Claims. (Cl. 188—62)

This invention relates to a retarder mechanism for railroad cars, and more particularly to inert retarder mechanisms wherein brake elements are disposed to engage the opposite sides of a car wheel to apply a decelerating force to the railroad car.

The present invention is directed to improvements in car retarders which characteristically employ pairs of opposed operating levers secured at their upper ends to the respective retarding elements and pivoted at their middle portions to a supporting bracket. The lower ends of the rotatable levers are biased by a compression spring to position the upper ends of the levers and the retarder elements so that the retarder elements are separated by a space less than the width of a car wheel. Thus, as a car wheel enters between the retarder elements, the car wheel forces the retarder elements to pivot away from each other against the biasing force of a compression spring while the retarding elements exert frictional forces on the sides of the car wheel.

Typically these car retarders receive rugged treatment due to the forces involved and exposure to the weather. While the car retarder must be rugged, the retarder also must be capable of ready installation and adjustment, particularly for compensating for wear of the brake element after considerable usage of the retarder. Accordingly, an object of the invention is a new and improved car retarder of unique construction with the capability of being readily adjusted by turning of adjustment elements.

Another object of the invention is a car retarder wherein the lever arms for the retarder elements have their pivot axis readily adjustable upon the turning of adjustment elements.

More specifically, and in accordance with a more specific object of the invention, the mounting brackets for the operating levers include elongated openings in which are disposed a pivot shaft for an operating lever, this pivot shaft being biased to retain each position to which the pivot shaft is moved by turning of appropriate adjustment elements.

The invention has another aspect, which is particularly manifested in another embodiment of the invention, wherein the position of the pivot axis for the levers can be readily attained without the requirement for costly machining operations to the components of the retarder. More specifically, a significant cost factor in a retarder of the type employing a bracket and pivot shaft is the machining of the shaft openings in the bracket and/or lever arms. Accordingly, a further object of the present invention is to eliminate the necessity of machining the shaft openings in the support bracket, and/or supporting lever arms for the retarder elements, thereby affording a retarder for lower cost.

More specifically, and under a further object of the invention, the shaft openings in the lever arms are cast oversize to readily accept the pivot shaft and the elongated openings in the supporting bracket and also cast oversize to receive shaft supporting blocks. Under this object of the invention, the shaft supporting blocks are translatable in the elongated openings to move the pivot axis in one direction, and the shaft supporting blocks can be revolved to move the pivot axis normal to the one direction. According to a further object of the invention, the pivot shaft for the lever arms is received in off-center openings in the supporting block so that rotation

2

and re-orientation of the supporting blocks causes a vertical movement of the pivot axis for the levers and thereby adjustment of the retarding elements.

Other and further objects of the present invention will be apparent from the following description and claims and are illustrated in the accompanying drawings which, by way of illustration, show preferred embodiments of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

In the drawings:

FIG. 1 is a plan view of a portion of a railroad track with a car retarder constructed in accordance with the present invention;

FIG. 2 is an end elevational view partly in section, of the car retarder;

FIG. 3 is a side elevational view of a lever arm assembly portion of the car retarder;

FIG. 4 is an enlarged view of an elongated slot and a screw adjustment for a pivot shaft according to another embodiment of the invention;

FIG. 5 is an end elevational view of a lever arm;

FIG. 6 is a front elevational view of a lever arm;

FIG. 7 is a plan elevational view of a lever arm;

FIG. 8 is a perspective view of a supporting bracket;

FIG. 9 is a perspective view of a lever arm;

FIG. 10 is an end elevational view of another embodiment of a car retarder in accordance with the present invention;

FIG. 11 is a side view of mounting of a lever arm of the embodiment of FIG. 10;

FIG. 12 is a front elevational view of a shaft supporting block;

FIG. 13 is a plan view of the shaft supporting block;

FIG. 14 is an end view of the shaft supporting block; and

FIG. 15 is an enlarged view of a shaft supporting block disposed in an elongated opening in the supporting bracket of the embodiment of the invention of FIG. 10.

Referring now to the drawings, and more particularly to FIG. 1, there is illustrated a portion of a railroad track, including a traffic rail 20 secured to a plurality of railroad ties 21. A car wheel (not shown) of a railroad car riding on the traffic rail 20 enters between a pair of retarding elements 24, which have their offset ends 25 and 26 flared divergently outward from the traffic rail 20 to constitute entrance mouths to direct the car wheel into the retarder and into engagement with the wheel engaging surfaces 28 on the opposed retarded elements 24.

The retarder elements 24 are secured to a plurality of independent levers or lever arms 30 disposed on opposite sides of the traffic rail 20 with their respectively associated retarding elements 24. Each of the lever arms 30 is pivotally mounted on a pivot shaft 32 for rotation about its respective pivot shaft to compress a compression spring 34 disposed between opposed lower portions 35 of a pair of opposed levers 30. Since the car wheel is of a greater width than the distance between the opposed surfaces 28 on the retarder elements 24, a car wheel moving between the

retarder elements 24 forces the retarder elements 24 outwardly away from each other and causes the lever arms 30 to rotate and to bring their lower portions 35 closer together against the resistance of the compression spring 34. Conversely, when the car wheel leaves the retarder, the compression spring 34 applies a force to the lower ends 35 of the respective levers 30 to pivot the respective levers 30 and thereby to move the lower ends 35

farther apart and bring the upper lever ends and retarder elements 24 closer together. The outward rotation of the bottom portions 30 of the respective levers is limited by a bolt and nut means 36 extending through apertures 37 in the lever arms 30 and through the compression spring 34.

For the purpose of supporting the pivot shafts 32, there is provided a pair of opposed support brackets 38 which are preferably secured opposite one another and to the web portion of the traffic rail 20 by a pair of spaced bolt and nut fasteners 39, FIGS. 2 and 3. While the brackets 38 are shown supported to the web of the traffic rail 20, it is to be understood that supporting brackets could be secured to the railroad ties in lieu of being secured directly to the rail and that a single bracket could be extended beneath the traffic rail 20 and substituted for the pairs of brackets 38. Each of the supporting brackets 38 has a pair of projecting lugs 40 spaced sufficiently far apart to receive a lever arm 30 therebetween. The lugs 40 extend outwardly from a cross plate portion 42, FIG. 8, in which are a pair of spaced apertures 43 for receiving bolt fasteners 39.

For the purpose of receiving a pivot shaft 32, each of the lugs 40 of a supporting bracket 38 has an elongated opening 45 extending generally horizontally, that is, when the supporting bracket 45 is affixed to the traffic rail 38, and terminating in rounded end walls. An elongated opening 45 is dimensioned to receive a pivot shaft 32 and permit the pivot shaft 32 to translate within the elongated opening 45 upon turning an adjustment screw 48 provided for this purpose.

The adjustment screw 48 is inserted through an oversized hole 49, FIG. 8, leading from the exterior of a lug 40 at an exteriorly rounded surface 50 to the elongated opening 45 in the interior of the lug 40. The adjusting screw 48 is not threaded in the openings 49, but is loosely received therein, and has its inner threaded end 52 threaded in a retainer nut 54 seated in a retainer seat 55 at the outer portion of the elongated opening 45. The retaining seat 55 is dimensioned so that the retaining nut 54 is disposed with its flat surfaces in engagement with the upper and lower side walls of the retainer seat 55. Thus, the retainer nut 54 is restrained from turning with rotation of the adjusting screw 48.

The biasing force of a compression spring 34 operating through the lever arm urges its associated pivot shaft 32 towards its further outermost position from the traffic rail 20. Thus, under the urging of the compression spring 34, the lever arms 30 force their respective pivot shafts 32 against the ends 52 of the adjusting screw 48 so that the pivot shafts 32 are resiliently biased in this position as the levers 30 rotate about the resiliently held pivot shafts 32.

Rotation of adjusting screws 48 and movement of their respective inner ends 52 further into the elongated openings 45 moves the associated pivot shaft 32 against the bias of compression spring 34. As pivot shafts 32 move inwardly, the retarding elements 24 are moved therewith and brought closer together to afford a greater braking force to a car wheel moving therebetween. Conversely, turning of the adjustment screws 48 outwardly to move the inner ends 52 of the screws 48 away from the traffic rail 20 permits the compression spring 34 to force the pivot shafts 32 outwardly from the traffic rail 20 and thereby increase the distance between the wheel engaging surfaces 28 of the retarder elements 24 and correspondingly decrease the retarding force applied to the car wheel.

As can best be seen in FIGS. 2 and 3, the pivot shafts 32 are held against axial movement by opposed cotter keys 60 disposed in apertures extending through the shafts and positioned against the outer surface walls 61 of a pair of spaced lugs 40. Preferably, the pivot shaft 32 is dimensioned to have a loose fit with the pivot seat or opening 54, FIG. 9, in a lever arm 30 so that the lever arm 30 is able to rotate slightly in an X and Y direction, FIG. 9, as the car wheel enters the retarder. Permitting

rotation of the levers 30 in the X and Y direction prevents undue stressing of the pivot shaft 32 as a car wheel enters between retarding elements 24. It is to be understood that the retarding elements 24 are firmly secured to the upper T-shaped portion 65 of the levers 30 by nut and bolt type fasteners 66. The lower openings 37 in each of the levers 30 for receiving bolts 69 are likewise oversize, as best seen in FIG. 2, so that the levers 30 can rotate slightly with their associated retarder element 34 in the X and Y direction, as well as permitting the lever arms to rotate about the pivot shafts 32 without binding on the shank of the bolt 69.

As explained hereinbefore, the amount of rotation of lever arms 30 about the pivot shaft 32 under influence of a compression spring 34 is limited by the spacing of a nut and bolt means 36, which includes a bolt head 69 on one side of the retarder and a washer 70 at the opposite side of the retarder. To vary the amount of rotation of the levers 30, the position of a washer 70 can be adjusted either by turning a nut 72 on the bolt 69 or by adding or replacing a shim 74 disposed between the washer 70 and nut 72.

The adjusting screw 38, hereinbefore described, was not threaded in the lug 40; however, it is possible to provide a tapped hole 78, FIG. 4, in the lug 40 to receive a threaded adjusting screw 79, FIG. 4, and thereby eliminate the need for a restraining nut 54. The adjusting screw 79, shown in FIG. 4, has secured to its inner end a flat seat 81 to provide a wider area for engagement with a pivot shaft 32. The seat 81 is secured by a set screw 80 which has inner point disposed in a groove in adjusting screw 80. Thus, the seat 81 need not turn with the adjusting screw 79, and therefore should not mark or score the pivot shaft 32 as easily as would an end 52 turning with an adjusting screw 38.

In the embodiment of the invention, illustrated in FIG. 10, the levers 30a support the retarder elements 24a for pivotal movement about the pivot shafts 32a against the biasing force of a compression spring 34a. The supporting brackets 40a differ from the supporting brackets 40 hereinbefore described in that elongated opening 90 in the bracket 40a is of a much larger size to receive a supporting block 91 for the pivot shaft 32a.

The shaft supporting block 91 has a circular opening 45 or shaft seat 92, FIG. 12, therein, which is offset from the center of the block, as can readily be seen in FIGS. 12 and 13. The center of the opening 92 is disposed at a different distance from each one of its four side walls 93 of the square sided block 91. Thus, rotating the block 91 through 90° will position the center line of the hole in a different position for each one of four different quarter revolutions.

To aid in ascertaining the position of a block 91, each block is provided with four spaced numerals 1, 2, 3 and 4 located about the aperture to designate, in ascending numerical order, the distance between the center of the aperture 92 and the bottom wall 95 of the elongated slot 90. The side wall of the slot is marked in corresponding numerals to show that the center line of the pivot shaft 32a can be disposed in any one of four alternative elevations, depending on which of the surfaces 93 of the block 91 is in engagement with the bottom surface 95 of the elongated slot 90.

As will be understood from the hereinbefore description, the turning of an adjusting screw 38a in a restraining nut 54a moves the threaded end 52a of the adjusting screw 38a to translate the block 91 within the elongated groove 90 toward the traffic rail 20. The pivot shafts 32 can be adjusted in a vertical direction by taking the blocks 91 from the elongated slots 90 and rotating them, and re-inserting them into the elongated slots 90. After a vertical adjustment, a pivot shaft 32 can be re-adjusted horizontally, if needed, by turning the adjusting screws 38a to cause or to permit the blocks 91 to slide in the elongated slots 90.

The retarder constructed in accordance with the embodiment of FIG. 10 eliminates costly machining of the holes 64 in the levers 30 and/or machining of the shaft seat openings in the lugs 40 of a supporting bracket.

Previously, the slot openings 45 or 90 were machined to obtain the proper positioning of elements relative to each other. With the rotatable blocks 91 and adjustment screws 38a none of the surfaces in the blocks 91, brackets 40a or levers 30a need to be machined to permit proper positioning, as was hereinbefore the case with prior car retarders of this general type. The cost of machining of openings in the brackets and/or levers of a retarder contributed significantly to the cost of the retarders. Thus, it will be seen that the present invention affords a unique adjustment for the pivot axis of a retarder lever which is rugged in construction and low in cost.

Hence, while preferred embodiments of the invention have been described and illustrated, it is to be understood that they are capable of variation and modification, and we therefore do not wish to be limited to the precise details set forth, but desire to avail ourselves of such changes and alterations as fall within the purview of the following claims.

We claim:

1. In a retarder mechanism for braking the car wheels of railroad cars comprising: retarder elements positioned parallel to a portion of a traffic rail and movable into engagement with opposite sides of a car wheel; a plurality of lever means disposed on opposite sides of said traffic rail, each of said lever means secured to a retarding element on its side of the traffic rail; bracket means for mounting said lever means, said bracket means having elongated slots therein; shaft means disposed in the elongated slots in said bracket means, said shaft means pivotally supporting said lever means; adjusting means for moving said shaft means within said elongated openings to change the position of said shaft means relative to the traffic rail so that the retarding elements also are moved relative to the traffic rail; resilient means urging the bottom portions of pairs of opposed lever means to urge the lever means of a pair to rotate about their respective shaft means, said resilient means holding said shaft means against said adjusting means in said elongated slot to prevent movement of said shaft means along said elongated slot toward traffic rail; and means for limiting the rotation of opposed lever means by its respective resilient means.

2. In a retarder mechanism for braking the car wheels of railroad cars comprising, retarding elements positioned parallel to a portion of a traffic rail and movable into engagement with opposite sides of a car wheel; a plurality of lever means disposed on opposite sides of the traffic rail, each of said lever means individually secured to a retarding element on its side of the traffic rail; bracket means secured to the rail for mounting said levers, said bracket means having elongated slots therein extending outwardly from said traffic rail; shaft means disposed in the elongated slots in said bracket means, said shaft means pivotally supporting said lever means; and adjusting screw means for moving said shaft means within said elongated openings to change the position of said shaft means relative to the traffic rail so that the retarding elements also are moved relative to the traffic rail, a resilient means urging a bottom portion of said lever means to rotate toward one another above the respective shaft means, said resilient means holding said shaft means against said adjusting screw means to prevent movement of said shaft means along said elongated slot toward said traffic rail.

3. The retarder mechanism of claim 2 wherein said adjusting screw means includes a threaded nut disposed in said elongated slot and held therein against turning and wherein said adjusting screw means includes a

threaded screw threaded into said nut and having its end for engagement with said shaft means.

4. In a retarder mechanism having a pair of opposed retarding elements disposed parallel to and slightly above a traffic rail to engage the sides of a car wheel of a railroad car moving over said traffic rail; a plurality of individual lever means secured to each of said retarder elements on opposite sides of said traffic rail; bracket means with elongated slots therein, said slots extending toward said traffic rail; a plurality of shaft means for individually mounting said lever means for rotation about their middle portions; a plurality of shaft supporting blocks each having an off-center opening therein for receiving a portion of a shaft means, said supporting blocks adapted to fit within said elongated openings and to be moved within said openings; and an adjustment means adapted to move said blocks within said elongated openings to reciprocate the position of a shaft means in one direction, said shaft means being adjustable in a second direction by removing said blocks from said elongated openings and turning said blocks to change the position of the off-center hole with respect to the elongated opening.

5. In a retarder mechanism having a pair of opposed retarding elements disposed parallel to and slightly above a traffic rail to engage the sides of a car wheel of a railroad car moving over said traffic rail; a plurality of individual lever means secured to each of said retarder elements on opposite sides of said traffic rail; bracket means with nonmachined slots cored therein, said slots being elongated and extending toward said traffic rail; a plurality of shaft means for individually mounting said lever means for rotation about their middle portions, said shaft means being fitted in unmachined and oversized openings in a lever means; a plurality of shaft supporting blocks having an off-center opening therein for receiving a portion of a shaft means, said supporting blocks adapted to fit within said elongated openings and to be translated within said openings; a plurality of adjustment screw means adapted to move respectively associated ones of said blocks within said elongated openings to change the position of a shaft means in one direction, said shaft means being adjustable in a second direction by turning said blocks to change the position of the off-center hole with respect to the elongated openings so that said shaft means can be moved in a second direction.

6. In a retarder mechanism having a pair of opposed retarding elements disposed parallel to and slightly above a traffic rail to engage the sides of a car wheel of a railroad car moving over said traffic rail; a plurality of individual lever means secured to each of said retarder elements on opposite sides of said traffic rail; bracket means with elongated slots therein, said slots extending toward said traffic rail; a plurality of shaft means for individually mounting said lever means for rotation about their middle portions; a plurality of shaft supporting blocks each having an off-center opening therein for receiving a portion of a shaft means, said supporting blocks adapted to fit within said elongated openings and to be moved within said openings; an adjustment means adapted to move said blocks within said elongated openings to reciprocate the position of a shaft means in one direction, said shaft means being adjustable in a second direction by removing said blocks from said elongated openings and turning said blocks to change the position of the off-center hole with respect to the elongated openings; and spring means urging the bottom portion of said lever means to rotate about said shaft means to move said retarding elements towards each other and urging said shaft means and the blocks supporting said shaft means outwardly of the elongated opening away from the traffic rail.

7. In a retarder mechanism having a pair of opposed retarding elements disposed parallel to and slightly above a traffic rail to engage the sides of a car wheel of a

railroad car moving over said traffic rail; a plurality of individual lever means secured to each of said retarder elements on opposite sides of said traffic rail; bracket means with nonmachined slots cored therein, said slots being elongated and extending toward said traffic rail; a plurality of shaft means for individually mounting said lever means for rotation about their middle portions, said shaft means being fitted in unmachined and oversized openings in a lever means; a plurality of shaft supporting blocks having an off-center opening therein for receiving a portion of a shaft means, said supporting blocks adapted to fit within said elongated openings and to be translated within said openings; a plurality of adjustment screw means adapted to move respectively associated ones of said blocks within said elongated openings to change the position of a shaft means in one direction, said shaft means being adjustable in a second direction by turning said blocks to change the position of the off-center hole with respect to the elongated openings so that said shaft means can be moved in a second direction; spring means for urging the lower ends of pairs of lever means outwardly, said spring means acting through said lever means to urge said shaft means against the adjustable screw means; and bolt means for limiting the rotation of the lever means by said spring means.

8. In a retarder mechanism having a pair of opposed retarding elements disposed parallel to and slightly above a traffic rail to engage the sides of a car wheel of a railroad car moving over said traffic rail; a plurality of individual lever means secured to each of said retarder elements on opposite sides of said traffic rail; bracket

means with elongated slots therein extending toward said traffic rail; a plurality of shaft means for individually mounting said lever means for rotation about their middle portions; a plurality of shaft supporting blocks having an off-center opening therein for receiving a portion of a shaft means, said blocks adapted to fit within said elongated openings and to be moved within said openings; adjustment screw means adapted to move said blocks within said elongated openings to change the position of a shaft means in one direction, said shaft means being adjustable in a second direction upon removing said blocks from said elongated openings and turning said blocks to change the position of the off-center holes with respect to the elongated opening so that position of said shaft means is changed in a second direction, said block being square in shape, and having the opening therein located at a different distance from each of four side walls of the square block, a plurality of indicia on said block indicative of the distance of the opening from an associated side wall of the block, and indicia on said bracket means corresponding to the indicia on said block indicative of the position of the opening of said block relative to a side wall of said elongated opening.
